LAST PULLING MACHINE

John T. Lancaster, Newtonville, Mass., assignor
to United Shoe Machinery Corporation, Paterson, N. J., a corporation of New Jersey

Application February 14, 1934, Serial No. 711,205
Renewed June 6, 1935

36 Claims. (Cl. 12—15.1)

This invention relates to machines for removing shoes from lasts and is herein disclosed as embodied in a machine having one or more members which, upon frictional engagement with a shoe on a last operate to urge the shoe off the last. For an example of a machine of this type reference may be had to United States Letters Patent No. 1,819,440, granted August 18, 1931, upon the application of Arthur F. Pym. In that machine a friction roll is provided for operating against the upper of the shoe at the rear end of the shoe to urge that portion of the shoe off the last and another friction roll is provided for operating against the forepart of the shoe for urging the forepart of the shoe off the last.

It is an object of the present invention to provide an improved machine of the type above mentioned wherein only a relatively slight pressure is necessary between the shoe and the shoe-engaging instrumentalities. In accordance with a feature of the invention, there is provided a pair of continuously moving members constructed and arranged for frictional engagement with the opposite sides respectively of a shoe on a last to urge the shoe off the last. In the illustrated machine, the continuously moving members consist of friction belts. These friction belts are angularly disposed relatively to each other with a V-shaped space between them and means is provided for moving a last support to bring the heel end of a shoe on the last into the V-shaped space and into frictional engagement with the belts. This construction, it will be noted, provides two shoe-engaging members located respectively upon opposite sides of the back seam, and, furthermore, each of these areas will be of considerable extent by reason of the fact that the friction belts are each capable of entering into engagement with a relatively large portion of the surface of the shoe. In accordance with a further feature of the invention there is provided a plurality of means engageable with different portions of the shoe respectively to urge the shoe off the last and also means for moving a last support to bring the shoe into engagement with one of the shoe-engaging means and for moving another of the shoe-engaging means into engagement with the shoe. In the illustrated machine the last support consists of a last pin mounted upon a lever which is moved to bring the upper of a heel end of a shoe on the last into engagement with a pair of driven friction belts. In the illustrated construction, a spring is included in the mechanism for moving the lever to enable the lever to yield, thereby avoiding ex-

cessive pressure between the shoe and the friction belts. After the heel end of the shoe has been moved heightwise off the last by these friction belts, another friction belt operates against the forepart of the shoe to urge that portion of the shoe forwardly off the last.

In the case of joined lasts, such as the two part hinged last illustrated herein, the removal of the rear portion of the shoe from the last is materially assisted by breaking the last as the rear end of the shoe is being urged off the last. Accordingly, a further feature of the invention consists of the provision of means for accomplishing this purpose. In the illustrated construction, the last is broken by moving the third-mentioned friction belt bodily against the tread surface of the forepart of the shoe. As soon as the last has been broken and the heel end of the shoe separated from the last, this third-mentioned friction belt, which is continuously driven, acts against the sole of the shoe to move the shoe forwardly off the last.

These and other features of the invention, including certain details of construction and combinations of parts, will now be set forth in connection with the illustrated machine and will be pointed out in the appended claims.

Referring now to the drawings,

Fig. 1 is a view in side elevation of a machine embodying the invention; 30

Fig. 2 is a view in front elevation of the machine;

Fig. 3 is a plan view of the machine;

Fig. 4 is a plan view of a portion of the mechanism shown in Fig. 3, showing this mechanism in a modified form; 35

Fig. 5 is a view in side elevation of the upper portion of the machine illustrating a more advanced stage of the operation; and

Fig. 6 is a view in side elevation of a portion of the operating mechanism of the machine. 40

The supporting structure of the machine consists of an upright frame or standard 10, having in its lower portion bearings 12 for a shaft 14. Loosely mounted upon the shaft 14 is a pulley 16 adapted to be driven from any convenient source of power. Fixed upon the shaft 16 is a pulley 18 in which is slidably mounted a dog 20. A spring 22, tending to urge the dog 20 into engagement with an abutment 24 on the drive pulley 16, is carried by the pulley 18. The dog 20 is normally held out of engagement with the abutment 24 by means of an arm 26 which engages a slot in the dog 20. The arm 26 is secured upon a rock-shaft 28 and is normally held down within the above- 50

55

mentioned slot by a spring 30. The shaft 28 is journaled in a bearing 32 carried in the lower portion of the frame 10. The shaft 28 carries an arm 34 which is engageable by a spring-pressed plate 36 carried by an arm 38 fulcrumed upon a pin 40 and having an extension in the form of a treadle 42. The dog 20 and the mechanism associated therewith constitute a one-revolution clutch. Upon depression of the treadle 42 the arm 26 will be rocked upwardly out of the slot in the dog 20, enabling the spring 22 to urge the dog into engagement with the abutment 24. The pulley 18 and the shaft 14 will now be driven by the pulley 16. Meanwhile the arm 26 will have been urged downwardly by the spring 30 into a position to enter the slot formed in the dog upon the completion of a revolution of the pulley 18. The free end of the arm 26 is tapered and serves as a wedge to retract the dog 20 from engagement with the abutment 24, thereby releasing the pulley 18 and the shaft 14 from driving engagement with the pulley 16.

In the upper portion of the frame 10 are bearings 44 for a shaft 46. A pulley 48 is secured upon one end of the shaft 46 and is driven by a belt 50 passing over the pulley 18. Extending from each of the bearings 44 is a bracket 52 in which is journaled a pulley 54. Extending from each side of the frame 10 is a bracket 56. The brackets 56 are each secured to the frame 10 with provision for heightwise adjustment relatively thereto by bolts 58. In each of the brackets 56 is journaled a pulley 60. One of the pulleys 60 is directly beneath one of the pulleys 54 and has its axis parallel to the axis of that pulley. Around these two pulleys runs a friction belt 62. The other pulleys 54 and 60 constitute a similar pair of supporting pulleys for a similar belt 62. The two pulleys 54 and likewise the two pulleys 60 have their axes inclined to each other so that the adjacent runs of the belts 62 are in substantially V-shaped relation to each other, although spaced a short distance from each other instead of meeting at the vertex. The two adjacent runs of the belt thus form substantially a dihedral angle with respect to each other, the vertex of the dihedral angle being parallel to the direction of movement of the adjacent runs. Each of the pulleys 54 carries a bevel gear 64. The gears 64 intermesh with each other and one of them is driven by a bevel gear 66 secured upon the shaft 46, the direction of drive being such as to cause the inner or adjacent runs of the belts 62 to travel upwardly. For supporting the inner run of each of the belts 62 against the pressure of the work, there is provided a set of five rolls 68. Extending forwardly from the frame 10 is a bracket 75 having a pair of diverging arms 72. Each of the arms 72, as shown in Fig. 3, is in the form of a yoke across which extend pins 69 upon which the rolls 68 are mounted.

Fulcrumed upon a pin 74 carried by the frame 10 is an upwardly extending lever 76. Extending from the upper end of the lever 76 is a last-pin 78. Pivotaly mounted upon a pair of pins 79 secured in the lever 76 are a pair of gage members 81 which are urged, by springs 83, respectively, into yielding engagement with the cone of a last on each side of the last pin 78 to center the last. The lever 76 is operated by a cam 89 secured upon the shaft 14 and having formed in one of its faces a track 82. Secured upon an arm 84 and engaging the track 82 is a roll 86. Extending from the arm 84 is a second arm 88. The arms 84 and 88 together constitute a bell crank and are both fulcrumed upon a pin 90 secured in the frame 10.

One end of a rod 92 is pivotally connected by a pin 94 to the outer end of the arm 88. Freely slideable upon the rod 92 is a sleeve 96 from which extends a pair of trunnion pins 98 which are received within bearings formed in lugs 100 extending from the lever 76. The outer end of the rod 92 passes through an opening in the lever 76 and carries a nut 102 which serves as an abutment for one end of a compression spring 104 surrounding the rod 92. The opposite end of the spring 104 bears against an end of the trunnion sleeve 96. A collar 105 secured upon the rod 92 serves as an abutment for the sleeve 96. The spring 104 normally holds the sleeve 96 against the collar 105, but will yield before the inward pull upon the lever 76 becomes excessive.

The last pin 78 consists of two sections, each in the form of a half cylinder, the two sections being pivotally mounted separately upon pins 106 secured in the lever 76. The two members constituting the pin 78 will normally, by reason of their own weight be in contact with each other along the entire length of the pin, and when in this condition the pin 78 will resemble an ordinary last pin. However, the two sections of the pin 78 may be forcibly separated by means of a plunger 108 having a wedge-shaped upper end engaging beveled surfaces formed upon each of the sections respectively of the pin 78. The plunger 108 is normally held down and out of engagement with the members of the pin 78 by a compression spring 110. Extending forwardly from the frame 10 is a bracket 112 having formed upon its outer end a sloping surface 114 adapted to be engaged by the lower end of the plunger 108 when the lever 76 swings inwardly. The effect of such engagement is to force the plunger 108 upwardly, separating the two members 78, or, in other words, expanding the last pin. In order to provide against breakage, the bracket 112 is not securely fixed to the frame 10 but is pivotally mounted upon a pin 116 carried by the frame 10. Bearing downwardly against a rearward extension of the bracket 112 is a coil compression spring 118. The rearward extension of the bracket 112 provides an upper abutment with the spring 118. A rod 120 extending within the spring 118 has its lower end pivotally connected to the rearward extension of the bracket 112. The upper portion of the rod 120 is freely slideable through the rearward extension of the bracket 112 and has secured upon its end a nut 122 which, by engagement with the rearward extension 114 limits the expansion of the spring 118 and determines the normal position of the bracket 112. It is evident that if too great pressure should be developed between the plunger 108 and the bracket 112, the spring 118 by yielding would prevent breakage.

Extending forwardly from the upper portion of the frame 10 and loosely pivoted upon the shaft 46 is an arm 124 having its forward or outer end forked. Journaled in the forward end of the arm 124 is a shaft 126 carrying a pulley 128. A pulley 130, fixed upon the shaft 46 drives the pulley 128 by means of a belt 132 passing around both pulleys. Loosely pivoted upon the shaft 126 is a frame comprising two side members 134 which are connected at their forward ends by a pin 136 and at their rear ends by a pin 138. Rotatably mounted upon the pin 136 is a pulley 140 and rotatably mounted on the pin 138 is a pulley 142. Fixed upon the shaft 126 is a driving pulley 144 for a belt 146. The belt 146 passes around the pulleys 140 and 142 and beneath and in driving engagement with the pulley 144. Sup-

ported by the frame members 134 is a bracket 148 carrying a plate 150 which provides a backing for the lower run of the belt 146. Pivotally connected to each of the frame members 134 is a 5 socket 152 for a link 154. Each of the links 154 passes slidably through a block 156 pivotally mounted in the lever 124. As shown in Fig. 3, the forked forward end of the lever 124 straddles the belt and pulley assembly above described. 10 Surrounding each of the links 154 is a spring 158 tending to urge the frame members 134 in a clockwise direction as viewed in Fig. 1. A nut 160 threaded upon the free end of each of the links 154 serves by engagement with the corresponding 15 block 156 to limit the movement of the frame members under the influence of the springs 158 and thereby to determine the normal position of the frame members relatively to the lever 124. Integral with the lever 124 and extending rearwardly therefrom is an arm 162 connected by a 20 rod 164 to a bell crank arm 166 (Figs. 1 and 6). Integral with the bell crank arm 166 is a second arm 168 carrying a roll 170 which engages a cam track 172 formed in the cam 80. The bell crank 25 comprising the arms 166 and 168 is fulcrumed upon the pin 90. In order to provide a yielding connection between the rod 164 and the arm 166 a sleeve 174 is trunnioned upon the outer end of the arm 166. The rod 164 is freely slideable 30 within the sleeve 174. Clamped upon the rod 164 is a collar 176. A compression spring 178 surrounding the rod 164 and interposed between the sleeve 174 and the collar 176 tends to urge the rod 164 upwardly relatively to the sleeve 174. 35 A nut 180 threaded upon the lower end of the rod 164 serves upon engagement with the sleeve 174 to limit such relative upward movement of the rod 164.

In the operation of the machine, a last L 40 having a shoe S thereon is mounted upon the last pin 78. The last L illustrated herein is a two part jointed last of the hinged type. The gages 81 will center the shoe to bring the back seam of the shoe about midway between the belts 45 62. The operator then depresses the treadle 42, tripping the above-described one-revolution clutch mechanism and starting rotation of the shaft 14. Rotation of the cam 80 will first rock the bell crank arms 84 and 88 in a clockwise direction as viewed in Fig. 6, thereby drawing the lever 76 inwardly and bringing the rear portion of the shoe upper into engagement with the friction belts 62. As the lever 76 swings inwardly, the plunger 108 will strike the cam surface 114, 50 thereby causing the last pin 78 to expand and grip securely the thimble hole of the last L. The pull of the rod 92 will be transmitted to the lever 76 through the spring 104. The thrust of the spring 104 and consequently the pressure of the shoe 55 against the belts 62 may be varied as desired by adjustment of the nut 102. The belts 62, each being backed by a plurality of small idler rolls rather than by a single roll, will each engage the shoe over a considerable area. Such areas of 60 engagement will be disposed at the counter portion of the shoe on opposite sides respectively of the center line. The belts will thus grip the rear end of the shoe between them; and as soon as such a grip is established, the upward travel of 65 the belts will raise the rear end of the shoe off the last L.

The arrangement of the cam tracks 82 and 172 is such as to cause the bell crank arms 168 and 166 to exert an upward thrust upon the rod 164 70 so as to bring the belt 146 into engagement with

the bottom of the forepart of the shoe at substantially the same instant that the heel end of the shoe engages the belts 62. As the rear end of the shoe is raised upwardly by the belt 62, the belt 146 will be urged downwardly causing the 5 last L to break as the rear end of the shoe is removed from the last. In Fig. 5 the last L is shown as completely broken. As the last in this position can yield no further, the continued upward thrust of the rod 164 will cause the belt 146 10 to develop sufficient friction against the shoe bottom to move the shoe forwardly upon the last L. The upward thrust of the arm 166 will be transmitted to the rod 164 through the spring 178, and the pressure between the shoe and the 15 belt 146 will therefore depend upon the spring 178. The supporting assembly of the belt 146 will rock about the shaft 126 to accommodate the angle of the shoe bottom, not only as the belt comes into engagement with the shoe bottom but 20 also during the breaking of the last. The cam track 82 is so formed as to release the lever 76 sufficiently, as soon as the heel end of the shoe has been removed, to enable the heel end of the last to be clear of the belts 62. Only a slight forward movement of the shoe is needed to loosen the forepart of the shoe from the last and consequently the cam track 172 is so shaped as to cause the lever 124 to be raised upwardly to its 25 normal position after only a relatively short operating engagement of the belt 146 with the shoe bottom. The operator then lifts the completely loosened shoe S from the last L, and the continued movement of the shaft returns the lever 76 forwardly to its initial position. Upon the 30 completion of the revolution of the shaft 14, the clutch mechanism above-described automatically becomes disengaged and the shaft 14 comes to rest, stopping the drive to the shaft 46 and to the belts 62 and 146. 40

It will be noted that the friction belts 62 and also the friction belt 146 are driven continuously during each cycle of the machine, and that the belts will therefore begin to act upon the shoe immediately upon the development of sufficient 45 pressure to provide the necessary friction.

In the machine as described up to this point the friction belts 62 are composed of rubber having a uniform thickness. As shown in Fig. 3, the pressure of the heel end of the shoe against the 50 belts causes the belts to yield, enabling the shoe to embed itself to some extent into the belts, thereby providing a moderate sized area of contact between the shoe and each of the belts. In Fig. 4, however, is shown a pair of improved belts 55 62' employed upon the same machine. Each of the belts 62' has formed in it a depression or groove 182 extending continuously all the way around the periphery of the belt. By reason of these grooves 182 a still greater area of contact 60 between the shoe and each of the belts may be obtained as well as a more uniform distribution of pressure over this area.

Having described the invention, what I claim 65 as new and desire to secure by Letters Patent of the United States is:

1. A machine for effecting relative movement of shoes and lasts comprising a support for a last with a shoe thereon, a plurality of means engageable with different portions of the shoe respectively to move the shoe relatively to the last, means for moving said last support to bring the shoe into engagement with one of said shoe-engaging means, and means for bringing another 70 75

of said shoe-engaging means into engagement with the shoe.

2. A machine for removing shoes from lasts comprising a support for a last with a shoe thereon, means engageable with the upper of the shoe to urge the shoe off the last, means engageable with the shoe bottom to urge the shoe off the last, means for moving said last support to bring the upper of the shoe into engagement with said upper-engageable means, and means for moving said bottom-engageable means into engagement with the shoe bottom.

3. A machine for removing shoes from lasts comprising a support for a last with a shoe thereon, a driven member frictionally engageable with the shoe upper for urging the shoe off the last, a driven member frictionally engageable with the shoe bottom for urging the shoe off the last, means for moving said last support to bring the shoe into engagement with said upper-engageable member, and means for moving said bottom-engageable member into engagement with the shoe.

4. A machine for removing shoes from lasts comprising a support for a last with a shoe thereon, a driven member frictionally engageable with the upper at the heel end of the shoe to urge the shoe off the last, a driven member frictionally engageable with the bottom of the forepart of the shoe to urge the shoe off the last, and means operable first to move said last support to bring the shoe against said upper-engageable member and then to press said bottom-engageable member against the shoe bottom.

5. A machine for removing shoes from lasts comprising a pin for engaging the thimble hole of a last with a shoe thereon, a lever upon which said last pin is mounted, a driven member frictionally engageable with the upper at the heel end of the shoe to urge the shoe off the last, a driven member frictionally engageable with the bottom of the forepart of the shoe, a lever upon which said bottom-engageable member is mounted, and means for moving said levers in timed relation to each other first to cause the upper of the heel end of the shoe to engage said upper-engageable member and then to bring said bottom-engageable member into engagement with the bottom of the forepart of the shoe.

6. A machine for removing shoes from lasts comprising a support for a last with a shoe thereon, means engageable with the upper of the shoe to urge the shoe off the last, means engageable with the shoe bottom to urge the shoe off the last, a driven cam, and operating connections between said cam and said last support and also between said cam and said bottom-engageable means, said cam and said operating connections being constructed and arranged to move said last support and said bottom engageable means in timed relation to each other first to bring the upper of the shoe into engagement with said upper-engageable means, and then to bring said bottom-engageable means into engagement with the shoe bottom.

7. A machine for effecting relative movement between shoes and lasts comprising a pair of members constructed and arranged for frictional engagement with the opposite sides respectively of a shoe on a last, and means for continuously moving said members to move the shoe relatively to the last.

8. A machine for removing shoes from lasts comprising a pair of members constructed and arranged to receive between them the heel end

of a shoe on a last, means for continually moving said members to cause said members by frictional engagement to urge the heel end of the shoe off the last, and means for holding the last against movement with the shoe.

9. A machine for removing shoes from lasts comprising a pair of driven members angularly disposed to each other with a V-shaped space between them, a support for a last with a shoe thereon, and means for moving said last support to bring the heel end of the shoe into said V-shaped space and into frictional engagement with said driven members, whereupon said driven members will urge the heel end of the shoe off the last.

10. A machine for effecting relative movement between shoes and lasts comprising a pair of driven belts constructed and arranged for frictional engagement with the opposite sides respectively of a shoe on a last to move the shoe relatively to the last.

11. A machine for removing shoes from lasts comprising a pair of driven friction belts having their adjacent runs disposed in substantially a dihedral angle with respect to each other, the vertex of the dihedral angle being substantially parallel to the direction of travel of said adjacent runs of the belts, and means for holding a last with a shoe thereon in position for the heel end of the shoe to engage said belts and to be moved by said belts off the last.

12. A machine for removing shoes from lasts comprising a pair of pulleys having their axes parallel to each other, a second pair of pulleys having their axes parallel to each other, the pulleys of each pair having their axes inclined relatively to the axes of the pulleys of the other pair, a friction belt traveling about each pair of pulleys, means for driving one pulley of each pair, a support for a last with a shoe thereon, and means for moving said last support to bring the heel end of the shoe into engagement with said belts, whereupon the heel end of the shoe will be separated from the last.

13. A machine for effecting relative movement of lasts and shoes comprising a support for a last with a shoe thereon, a belt frictionally engageable with the shoe to move the shoe relatively to the last, a pair of pulleys around which said belt travels, means for driving one of said pulleys, and a backing member positioned between said pulleys for supporting said belt against the pressure of the work.

14. A machine for removing shoes from lasts comprising a support for a last with a shoe thereon, a belt frictionally engageable with the shoe to urge the shoe off the last, and a backing plate for supporting said belt against the pressure of the work.

15. A machine for removing shoes from lasts comprising a support for a last with a shoe thereon, a belt frictionally engageable with the shoe to urge the shoe off the last, a pair of pulleys around which said belt travels, means for driving one of said pulleys, and a plurality of rolls positioned between said pulleys for supporting said belt against the pressure of the work.

16. In a machine for removing shoes from lasts, a driven belt frictionally engageable with a shoe on a last to urge the shoe off the last, and a plurality of rolls of relatively small diameter and relatively close to each other for supporting said belt against the pressure of the work.

17. A machine for removing shoes from lasts comprising a support for a last with a shoe there-

on, a belt frictionally engageable with the shoe to move the shoe relatively to the last, a pair of pulleys upon which said belt is mounted, driving means for one of said pulleys, a frame in which 5 said pulleys are journaled, an arm for supporting said frame, means for moving said arm to bring said belt into operative engagement with the shoe, and a pivotal connection between said frame and said arm to enable said frame to tilt 10 as the belt presses against the shoe.

18. A machine for removing shoes from lasts comprising a support for a last with a shoe thereon, a belt frictionally engageable with the shoe to move the shoe relatively to the last, a pair of 15 pulleys upon which said belt is mounted, driving means for one of said pulleys, a frame in which said pulleys are journaled, and means for moving said frame to cause said belt to engage the shoe at a locality between said pulleys.

19. A machine for removing shoes from lasts comprising a support for a last with a shoe thereon, a belt frictionally engageable with the shoe to move the shoe relatively to the last, a pair of 20 pulleys upon which said belt is mounted, driving means for one of said pulleys, a frame in which 25 said pulleys are journaled, means for moving said frame to cause said belt to engage the shoe at a locality between said pulleys, and means positioned between said pulleys for supporting 30 said belt against the pressure of the shoe.

20. A machine for removing shoes from lasts comprising an expandable pin for engaging the thimble hole of a last with a shoe thereon, a friction member engageable with the outside of the 35 shoe, means for effecting relative movement between said last pin and said friction member to cause relative movement of separation between the shoe and the last, and means for expanding 40 said last pin to grip the last.

21. A machine for removing shoes from lasts 45 comprising an expandable pin for engaging the thimble hole of a last with a shoe thereon, a friction member driven in a direction to separate the shoe from the last, means for moving said last pin to bring the shoe into operative engagement with said friction member, and means operable upon movement of said last pin toward said friction member to expand said last pin.

22. A machine for removing shoes from lasts 50 comprising an expandable pin for engaging the thimble hole of a last with a shoe thereon, a support for said last pin, a rotary friction member driven in a direction to separate the shoe from the last, means for moving said last pin support to bring the shoe into operative engagement with said friction member, mechanism carried by said last pin support for expanding said last pin, and a relatively stationary member positioned in the path of said mechanism for operating said 55 mechanism to expand the last pin as the last pin is moved toward said friction member.

23. A machine for removing shoes from lasts 60 comprising a support for a last with a shoe thereon, a friction member engageable with the exterior of a shoe, means for moving said last support to cause the shoe on the last to press against said friction member, a spring in said moving means for enabling said last support to yield under the pressure of the shoe against the friction member, and means operable while the shoe is pressed against said friction member to move the friction member in a direction to separate the shoe from the last.

24. A machine for removing shoes from lasts 65 comprising a lever, a last pin on said lever for

supporting a last with a shoe thereon, a friction member, power driven mechanism for swinging said lever to cause the rear portion of the shoe on said last to press against said friction member, a spring in said mechanism for enabling the 5 lever to yield under the pressure of the shoe against the friction member, and means operable while the shoe is pressed against said friction member to move the friction member in a direction to raise the rear portion of the shoe relatively to the last. 10

25. A machine for removing shoes from lasts comprising an upstanding lever, a fixed fulcrum upon which the lower end of said lever is pivotally mounted, a friction member, a power driven 15 crank, a link for transmitting movement from said crank to said lever to swing the lever toward said friction member to cause the rear portion of the shoe on the last to press against the friction member, a spring interposed between said lever and said link for enabling said lever to yield under the pressure of the shoe against the friction member, and means for moving said friction member upwardly to raise the rear portion of the shoe 20 relatively to the last. 25

26. A machine for removing shoes from lasts comprising a support for a last with a shoe thereon, a friction member engageable with the exterior of a shoe, power driven means for moving said last support first to cause the shoe on 30 the last to press against said friction member and for then moving the last support away from the friction member, means operable while the shoe is pressed against said friction member to move the friction member in a direction to separate the 35 shoe from the last, and cyclic control mechanism constructed and arranged to start the operation of said power driven means under control of the operator and automatically to stop the operation of said power driven means when the last support occupies a position away from the friction member. 40

27. A machine for removing shoes from lasts comprising a support for a last with a shoe thereon, a friction member engageable with the exterior of a shoe, means for moving said last support first to cause the shoe on the last to press against said friction member and for then moving the last support away from the friction member, power driven mechanism for operating said 45 means for moving the last support, means operable while the shoe is pressed against said friction member to move the friction member in a direction to separate the shoe from the last, a clutch in said power driven mechanism, operator 50 controlled means for engaging said clutch to start the operation of said means for moving said last support, and means for disengaging said clutch automatically when the last support occupies a 55 position away from the friction member. 60

28. A machine for removing shoes from jointed lasts, comprising means for removing the rear portion of a shoe from a last, and means operable during the removal of the rear portion of the shoe from the last to break the last. 65

29. A machine for removing shoes from jointed lasts, comprising a support for a last with a shoe thereon, a member engageable with the rear portion of the shoe, means for effecting relative movement between said last support and said 70 member to cause the rear portion of the shoe to be removed from the last, and means operable during the removal of the rear portion of the shoe from the last to break the last. 75

30. A machine for removing shoes from jointed 75

lasts, comprising a support for a last with a shoe thereon, means for exerting a force upon the rear portion of the shoe to remove the rear portion of the shoe from the last, and means for simultaneously exerting pressure against the tread surface of the forepart of the shoe to break the last.

31. A machine for removing shoes from jointed lasts, comprising a support for a last with a shoe thereon, means operable by frictional engagement with the rear portion of the shoe to remove the rear portion of the shoe from the last, a member engageable with the tread surface of the forepart of the shoe, and means operable in timed relation to the removal of the rear portion of the shoe from the last to cause said member to press against the tread surface of the forepart of the shoe to break the last.

32. A machine for removing shoes from jointed lasts, comprising a support for a last with a shoe thereon, a friction member engageable with the exterior surface of the upper of the shoe, means for moving said last support to effect engagement between said friction member and the exterior surface of the shoe upper, means for moving said friction member to cause the friction member to remove the rear portion of the shoe from the last, and means engageable with the forepart of the shoe and operable in timed relation to the removal of the rear portion of the shoe from the last to break the last.

33. A machine for removing shoes from jointed lasts, comprising a support for a last with a shoe thereon, a driven member normally out of engagement with the shoe and constructed and arranged to remove the rear portion of the shoe from the last when in engagement with the rear portion of the shoe, a member engageable with the forepart of the shoe to break the last, and a cam mechanism for effecting relative movement between said last support and said driven member to cause engagement between the rear portion of the shoe and said driven member to

enable said driven member to remove the rear portion of the shoe from the last, said cam mechanism serving also to operate the forepart-engageable member to cause the last to be broken.

34. A machine for removing shoes from jointed lasts, comprising means for removing the rear portion of a shoe from a last, and means operable first to break the last in timed relation to the removal of the rear portion of the shoe and then to remove the forepart of the shoe from the last.

35. A machine for removing shoes from jointed lasts, comprising a support for a last with a shoe thereon, means engageable with the rear portion of the shoe to remove the rear portion of the shoe from the last, a member engageable with the forepart of the shoe, and means for operating said member first to cause the last to be broken in timed relation to the operation of the rear portion engageable means and then to remove the forepart of the shoe from the last.

36. A machine for removing shoes from jointed lasts, comprising a support for a last with a shoe thereon, a driven member frictionally engageable with the rear portion of the shoe to urge the rear portion of the shoe off the last, means for moving said last support to effect engagement between the rear portion of the shoe and said driven member to cause the rear end of the shoe to be removed from the last, a member frictionally engageable with the tread surface of the forepart of the shoe, means for moving the second-mentioned member against the tread surface of the forepart of the shoe to break the last while the rear portion of the shoe is being removed from the last, and means for driving the second-mentioned member in a direction to cause it to move the forepart of the shoe off the last when the last is completely broken and the rear end of the shoe is off the last.

JOHN T. LANCASTER.
